(57) **CLAIM**

We claim the ornamental design for a ventilation fan, as shown and described.

DESCRIPTION

FIG. 1 is a top perspective view of a ventilation fan; FIG. 2 is a top view of a ventilation fan of FIG. 1; FIG. 3 is a front side view of a ventilation fan of FIG. 1; FIG. 4 is a side view of a ventilation fan of FIG. 1; and, FIG. 5 is a bottom view of a ventilation fan of FIG. 1. The features shown in broken lines depict environmental subject matter only and form no part of the claimed design.
